UNITED STATES PATENT OFFICE.

FRANK RADFORD AND EDWARD C. BOYER, OF DAYTON, OHIO.

DESIGN FOR A CLAMP MEMBER.

SPECIFICATION forming part of Design No. 29,920, dated January 3, 1899.

Application filed November 21, 1898. Serial No. 697,103. Term of patent 7 years.

To all whom it may concern:

Be it known that we, FRANK RADFORD and EDWARD C. BOYER, citizens of the United States, residing at Dayton, in the county of 5 Montgomery and State of Ohio, have invented and produced a new and original Design for a Clamp Member, of which the following is a specification, reference being had to the accompanying drawings, forming part thereof, and in which like characters of reference refer to correspondingly-formed parts.

Our invention relates to a design for a clamp member for use more especially in grinding-machines.

15 Figure 1 is a rear elevation of a clamp member formed in accordance with our new and useful design. Fig. 2 is a front elevation thereof. Fig. 3 is a top plan view thereof; and Fig. 4 is a sectional view thereof on line 20 $\alpha\alpha$ of Fig. 3, these four views being deemed necessary to fully illustrate our design.

From opposite ends of the horizontal bar A are upward extensions B, terminating in

forward projections C. Centrally upon the front side of said bar is a projection D. 25 Near the opposite ends of and projecting from the lower side of said bar A are straight arms E, having lugs F on one side of the ends of each of said arms E and projecting beyond one edge of said arms E. 30

The essential feature of our design for a clamp member consists of a horizontal bar with upward and forwardly projecting extensions and downwardly-projecting arms near the ends of said bar and a central forward 35 projection on said bar.

What we claim is—

The design for a clamp member, substantially as herein shown and described.

In witness whereof we have hereunto set 40 our hands this 24th day of October, 1898.

FRANK RADFORD.
EDWARD C. BOYER.
